UNITED STATES PATENT OFFICE.

WILLIAM R. JEAVONS AND ARNOLD R. WHITTAKER, OF CLEVELAND, OHIO.

OIL-STOVE.

1,259,628.

Specification of Letters Patent.

Patented Mar. 19, 1918.

Original application filed August 4, 1914, Serial No. 855,044. Divided and this application filed April 9, 1917. Serial No. 160,611.

To all whom it may concern:

Be it known that we, (1) WILLIAM R. JEAVONS, (2) ARNOLD R. WHITTAKER, citizens of the United States, residing at Cleveland, in the county of Cuyahoga and State of Ohio, have invented a certain new and useful Improvement in Oil-Stoves, of which the following is a full, clear, and exact description, reference being had to the accompanying drawings.

This invention relates to oil stoves and more particularly to stoves of the type which are known to the trade as "heaters" or "lamp stoves." One of the objects of the invention is to provide a construction and arrangement of parts whereby, on the one hand, the oil in the font may be heated to a temperature suitable to reduce its viscosity and to secure an efficient supply of the same to the vaporization point by the wick and, on the other hand, to prevent the overheating of the font and to keep the parts adjacent to the burner comparatively cool. A further object of the invention is to provide a construction of oil stove or heater which will deliver a large amount of heat nearer the floor than is the case with any previous type of heater with which we are familiar and one wherein, notwithstanding the proximity of the flame to the font and the lower parts of the heater frame, these parts will not become heated to such a temperature as to prevent them from being handled without discomfort.

In the operation of our heater, the temperature of the oil in the top of the font will be maintained at approximately 115° F.—a temperature which reduces the viscosity of the oil to an extent that will insure a uniformly ample capillary feed to the exposed surface of the wick, notwithstanding the lowering of the oil level in the font during a long continued operation. This temperature, on the other hand, will not unduly reduce such viscosity and produce an undue vaporization of the oil within the top of the font. The invention disclosed herein is a division of our application No. 855,044 filed August 4, 1914.

In the drawings forming a part hereof, Figure 1 represents a view, partly in section and partly in elevation, of a stove constructed in accordance with our invention; and Fig. 2 a transverse sectional view cor-

responding to the line 2—2 of Fig. 1, certain 55 of the parts being broken away.

Describing by reference characters the various parts illustrated herein, 1 denotes a stove base having the legs 2. At its upper end, the base is provided with a bead 1^a and a plurality of inwardly projecting segmental flanges 3 each having bosses 3^a pressed upwardly therefrom. 4 denotes the font, which is mounted within the base and is supported on the upwardly projecting bosses 65 3^a by means of the substantially horizontal flange 5 at the top of the body of the font. It will be observed that slots 3^b are provided between the segmental flanges and between the flange 5 and the body of the font. The 70 font is a shallow metal reservoir having central vertically alined openings through which extends the outer wick tube 6. The top and the bottom of the font are substantially horizontal and are preferably provided with shallow annular ribs or corrugations 7 and 8 between the peripheral and central portions thereof. Projecting downwardly from the bottom and extending around the bottoms of the wick tubes 6 is a 80 wind shield 9 having perforations 10 in the outer wall thereof, the wind shield being of the type described and claimed in the application of William R. Jeavons No. 782,005, filed July 30, 1913, Patent No. 1,218,777. 85

Projecting upwardly from the upper end of the inner wick tube is the air distributor, indicated generally at 11. This distributor may be of any approved type, such as shown in the patent to Jeavons No. 906,887, issued 90 December 15, 1908, and causes the flame to spread outwardly as it rises. Projecting upwardly from the top of the font, and surrounding the upper end of the outer wick tube 6, is a perforated collar or gallery 12, 95 which preferably extends upwardly about as high as the outer wick tube and is there bent outwardly in an inverted U-shape, as shown at 13, forming a seat for a collar 14 projecting downwardly from a central opening within an obliquely extending diaphragm or partition forming the perforated bottom 15 of the stove drum or casing 16. The collar is projected outwardly, as shown at 14^a, to provide a seating portion co-operating 100 with the top of the gallery 12, the lower end of the collar projecting downwardly below the top of the gallery and being flared out-

wardly, as shown at 14^b. The particular construction of the gallery forms the subject matter of a copending application No. 855,045, filed August 4, 1914.

- 5 The bottom 15 of the drum is preferably formed by an inwardly projecting portion of the drum base (known to the trade as the "cone plate") which forms a cover for the outer portion of the font and which is provided with an annular seat 15^a for the lower end of the drum and which base extends outwardly beyond the top of the font and is seated within the bead 1^a, when the drum is in operative relation to the burner.
- 15 The drum base affords the means by which the drum or casing is hinged to the stove base 1. The portion of the drum base between the drum and the stovebase is provided with perforations 15^b. Two circular 20 rows of perforations are shown, each row extending entirely around the drum base, the lower row being located in proximity to the top of the font, whereby the entering air may pass in close proximity to such top. 17
- 25 denotes an obliquely extending diaphragm or partition forming a false bottom for the drum, said false bottom extending upwardly and outwardly from the inner periphery of the drum base 15 and substantially parallel 30 with the flame of the burner. The inner edge of the drum base 15 and the inner edge of the false bottom 17 may be conveniently clamped by the upper end of the collar 14, such upper end being shown as bent into 35 channel form, as shown at 14^c, to receive therewithin the horizontal flanges formed at the inner peripheries of the parts 15 and 17. The outer end of the false bottom 17 abuts against the inner surface of the drum 16 and 40 may be provided with an upwardly projecting flange 17^a, bearing against and secured to such drum surface. Between the false bottom, the drum bottom and the lower portion of the drum there is formed an annular 45 chamber 18 which is closed at its inner edge and through which the air from beneath may circulate, it being observed that the lower part of the drum proper is provided with perforations of an ornamental character, indicated at 16^a, located between the drum bottom 15 and the false bottom 17. The air will circulate upwardly through the perforations 15^c in the false bottom, through the chamber 18 and outwardly through the perforations 55 16^a. The chamber 18 is isolated from the combustion space within the drum or casing by the diaphragm or false bottom 17.
- 60 As is the case with the construction shown in the Jeavons patent No. 1,089,841, the oil font 4 is extremely shallow, as compared with its lateral extent. In this case, as in the case with the patented construction, it is contemplated that the oil shall not be fed by capillary action a distance materially 65 greater than five inches and that the top of

the wick tube shall be not materially greater than 1½ inches from the top of the font. This insures the maintenance of the oil below the seepage limit and within the capillary limits of the wick, while the oil travels 70 by capillarity, at all times, in sufficient quantity to keep the exposed surface of the wick well supplied. Furthermore, as is the case with the construction of the Jeavons patent aforesaid, the relation of the parts beneath 75 and heated by the flame to the extended top of the font is such as to warm the oil to a temperature of at least 110°. It has been found that the best results are secured when the temperature of the oil is maintained at 80 substantially 115° and does not materially exceed such temperature as such temperature reduces the viscosity of the oil to such an extent as to insure an ample capillary feed, while an over-supply of vapor from 85 the top of the wick to the flame is prevented. This result is secured in and through the construction and arrangement of parts just described in connection with the false bottom 17 and the arrangement whereby relatively cool air is circulated about the top of the font and beneath the false bottom. 90 As will be seen by reference to the arrows in Fig. 1, air passes upwardly through the slots 3^b and through the openings 15^b and 95 passes above the top of the font. The collar 14 serves to deflect some of this air through the gallery 12 to the outer portion of the flame burning above the top of the wick tubes, the remainder of the air being directed and deflected by the collar through the perforations 15^c in the drum bottom 15. The greater portion of the air deflected by the collar 14 passes through the chamber 18, being delivered from said chamber through 100 the openings 16^a in the lower end of the drum proper.

It will be noted that, in maintaining the temperature in the top of the font at about and not materially exceeding 115° F. we 110 secure a circulation of relatively cool air about and above the top of the font and in proximity to the parts adjacent to and beneath the burner, whereby these parts are kept relatively cool—an important consideration in itself and one of the objects attained by our invention; also that we secure these results in and through a construction of heater which will deliver a large amount of heat nearer the floor than in any previous 115 type of heater with which we are familiar; and that, notwithstanding the proximity of the flame to the reservoir and to the lower parts of the heater frame, we preserve these parts at such a temperature that they may 120 be handled without discomfort. For instance, the temperature of the inner portion of the drum base has been reduced by this construction from between 400 to 500° F. to between 200 to 250° F. and the part 125 130

of the drum base located outside of the drum is sufficiently cool to be handled without discomfort. Although the top of the reservoir is intentionally subject to radiant heat from the drum base, the heating effect is kept within the most efficient limits by the air distributing arrangement provided herein.

The chamber provided between the partition 17, the partition formed by the drum bottom, and the lower portion of the drum is out of communication with the combustion space thereabove, although air can circulate therethrough. Furthermore, it will be noted that the openings 16^a are relatively large so that the outer wall of this chamber offers no substantial resistance to the outward radiation of heat from the inclined partition 17. By this arrangement, the top 20 of the font or reservoir is heated only to the temperature desired.

Having thus described our invention, what we claim is:—

1. In a device of the character described, the combination of a casing inclosing a combustion space, a burner in said combustion space, a reservoir for liquid fuel, a diaphragm extending from the burner to the casing and between the combustion space and the reservoir, a cover below the diaphragm, said cover and the casing above it having openings, the said diaphragm and

cover and the casing extending from one to the other forming a chamber interposed between the combustion space and the reservoir and the said openings providing for the entrance of air at the lower part of said chamber and the egress of air at the upper part thereof, and the said diaphragm cutting off the said chamber from communication with the combustion space, and means for supplying air to the said chamber from points adjacent to the tank and for directing a portion of the air from such points into the combustion space before it reaches the said chamber.

2. The combination of a shell or casing inclosing a space for combustion, a liquid fuel reservoir below the said combustion space and an imperforate diaphragm within the casing interposed between the combustion space and the reservoir, a cover extending over the said reservoir below the said diaphragm and provided with openings for the passage of air therethrough to a space above it and below the diaphragm said cover being spaced from the said reservoir so as to form a passage for the air between it and said reservoir, and to the said openings.

In testimony whereof, we hereunto affix our signatures.

WILLIAM R. JEAVONS.
ARNOLD R. WHITTAKER.
